(57) **CLAIM**

The ornamental design for a multi-purpose tackle, as shown and described.

DESCRIPTION

FIG. 1 is a front perspective view of a multi-purpose tackle; FIG. 2 is an exploded perspective view thereof; FIG. 3 is a left side elevation view thereof, the right side being a mirror image thereof; FIG. 4 is a bottom plan view thereof; FIG. 5 is a top plan view thereof; FIG. 6 is a side sectional view thereof taken along line 6-6 of FIG. 3; FIG. 7 is rear elevation view, the front elevation view being a mirror image thereof; FIG. 8 is a side sectional view of FIG. 6 shown in an in-use baited condition; FIG. 9 is the side sectional view of FIG. 6 shown in an in-use caught condition with a crustacean; and, FIG. 10 is the side sectional view of FIG. 6 shown in an in-use caught condition with a fish.

The broken lines in FIG. 8-10 depict environmental structure (fishing line, hook, worm, and crab claw) that form no part of the claim. The broken lines in the drawings depict portions of the design that form no part of the claim.

1 Claim, 8 Drawing Sheets
